(57) **CLAIM**

The ornamental design for a motorized change-over switch, as shown and described.

DESCRIPTION

FIG. 1 is a top, front perspective view of a motorized change-over switch showing a first embodiment of our new design.

FIG. 2 is a top plan view thereof.

FIG. 3 is a bottom plan view thereof.

FIG. 4 is a front elevational view thereof.

FIG. 5 is a right side elevational view thereof.

FIG. 6 is a left side elevational view thereof.

FIG. 7 is a bottom, rear perspective view thereof.

FIG. 8 is a top, front perspective view of a motorized change-over switch showing a second embodiment of our new design.

FIG. 9 is a top plan view thereof.

FIG. 10 is a bottom plan view thereof.

FIG. 11 is a front elevational view thereof.

FIG. 12 is a right side elevational view thereof.

FIG. 13 is a left side elevational view thereof; and,

FIG. 14 is a bottom, rear perspective view thereof.

The broken line showing of various elements of the motorized change-over switch is for illustration purposes only and forms no part of the claimed design.
